CLAIM

The ornamental design for a photocuring device, as shown and described.

DESCRIPTION

FIG. 1 is a front, top, right perspective view of a photocuring device, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an additional rear view showing the photocuring device in a state of use.

The dash dot dash broken lines illustrate the boundary of the design. The remaining broken lines illustrate portions of the photocuring device. None of the broken lines form part of the claimed design.

Nail Alliance is the owner of the registered trademark "Gelish".
